B. R. HAWLEY, OF NORMAL, ILLINOIS, ASSIGNOR TO HIMSELF, E. WASH-BURN, AND C. A. MONTROSS.

Letters Patent No. 66,334, dated July 2, 1867.

IMPROVED SORGHUM-EVAPORATOR.

The Schedule referred to in these Letters Patent and making part of the same.

TO ALL WHOM IT MAY CONCERN:

Be it known that I, B. R. HAWLEY, of Normal, in the county of McLean, and State of Illinois, have invented a new and useful improvement in Evaporators; and I do hereby declare that the following is a full and clear description thereof, reference being had to the accompanying drawings, and to the letters of reference marked thereon.

This invention relates, firstly, to an outside pocket, attached to the side of the boiling-pan, and through the side wall of which an aperture is made into the said pocket, at or near its bottom. The outside wall of the pocket extends up higher than the side wall of the boiler, which forms the partition between it and the said pocket. This construction allows the boiling fluid from the boiler to flow over into the pocket, where it becomes cooled and settles downward, by reason of its increased specific gravity, and then again enters the boiler, at or near its bottom, through the aforesaid aperture. After re-entering the boiler the fluid again becomes heated, and rises to the surface, to again flow over into the pocket, and thus a continuous upward and downward flow is maintained during the whole of the boiling process. The pocket formed, as above described, may have a strainer placed over its top, so as to exclude the coarser impurities of the boiling scum, and its entire cavity may be filled with raw wool, as a filtering material.

This invention also relates to a cooler for receiving the finished sirup, and retaining it until cooled off preparatory to its package for market or use. The details of the mechanical construction of the improved parts will be clearly understood by reference to the accompanying drawings. As it is the purpose of the inventor to apply these improvements to an evaporator patented by himself on the first day of May, A. D. 1866, and numbered 54,340, the said evaporator, so patented, will be herein represented and described, so far as may be necessary to the illustration of the present invention. It is not, however, to be understood that the improvements herein described are to be exclusively employed on the said evaporator, but are to be equally applicable to any other form of evaporators.

To enable those skilled in the art to make and use my improved evaporator, I will proceed to describe its construction and operation.

Figure 1 of the drawings is a general plan of the improved evaporator and its side pockets, or straining attachments.

Figure 2 is a side elevation of the same.

Figure 3 is a transverse sectional elevation of it.

In the drawings, A represents the primary boiler, B the defecator, and C the finishing-pan. The construction and arrangement of the foregoing parts are much the same as similar parts in the former patent. In the present instance, however, a fluid-chamber is left between the front of the fire-box and the wooden wall enclosing the same, as well as the two chambers at the sides of the fire-box, as in the former patent. The general construction and arrangement of the primary boiler A, the defecator B, and the finishing-pan C are much the same as they were in the former patent. The first and principal feature of the improvement consists in adding to the sides of the primary boiler, and to the defecator, an external pocket, D, which may be made of sheet metal and securely affixed to the exterior face of the wooden enclosing wall, through which an aperture, d, is made at or near the bottom of the said pocket. The outside and end walls of the pockets D are made higher than the enclosing wooden wall of the boiler, so that the fluid within the boiler is allowed to boil over into the pockets D, where it becomes cooled off and settles down to the bottom of the pocket, whence it again enters the boiling-pan or defecator, as the case may be, through the aperture d, and then again becomes heated and rises to the surface, to again flow over into the straining-pocket D, and thus a continuous upward and downward flow of the boiling sirup is kept up in the directions of the arrows a a', and this flow of the said fluid is kept up for the purpose of straining the sirup while boiling, through the strainer D', placed over the top of the pocket D, and also for the purpose of filtering the fluid by passing it down through a filtering material, d', which is placed within the pocket D. The said filtering material may be of raw wool, or any equivalent material.

I am perfectly well aware that raw wool, as a filtering material for sirups and other like purposes, is already the subject of Letters Patent, therefore it is only the aforesaid application that is the subject of this invention.

In the present invention I place a cooler, E, (which is simply a shallow pan,) below the finishing-pan C and the defecator B. An aperture, e, in the side of the wooden wall, admits the exterior atmosphere to the sirup in the cooler, so as to reduce the temperature of it sufficiently for the purpose of drawing off for barrelling or packing. The finished sirup may be drawn from the finishing-pan C directly into the cooler, through the pipe e¹ and the stop-cock e², and may be drawn off from the cooler at leisure through the pipe e³ and stop-cock e⁴, into the barrel or other package, ready for market. This arrangement of cooler affords a convenience as to the mode and time of disposing of the finished sirup.

Having described my invention, what I claim, is—

1. The construction of an evaporating-pan in such a manner as to create a continuous upward and downward flow of the boiling sirup, as represented by the arrows a a', substantially in the manner and for the purpose set forth.
2. I claim the filtering-pockets D, in combination with the boiling-pans or defecator of an evaporating apparatus, substantially in the manner and for the purpose set forth.
3. I claim the cooler E, in combination with the finishing-pan C, as described and set forth.
4. I claim filtering the boiling sirup by continuously passing its surface fluid down through a filtering substance in the pocket D, to the bottom of the boiler, substantially in the manner and for the purpose set forth.
5. I claim the strainers D', in combination with the boiling-pans or defecator, and the pockets D, substantially as described and set forth.

B. R. HAWLEY.
